OTHER PUBLICATIONS

U.S. Notice of Allowance dated Oct. 25, 2017, from U.S. Appl. No. 29/576,367, filed Sep. 2, 2016, 14 pages.

Primary Examiner — George D. Kirschbaum*Assistant Examiner* — Natasha Vujcic(74) *Attorney, Agent, or Firm* — Rankin, Hill & Clark LLP(57) **CLAIM**

The ornamental design for a LED endcap, as shown and described.

DESCRIPTION

FIG. 1 is a front top perspective view of an LED endcap; FIG. 2 is a rear bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of usage thereof.

The broken lines in the drawings, which illustrate environmental structure or boundaries of the LED endcap, do not form a part of the claimed design.

1 Claim, 7 Drawing Sheets(56)
